(57) **CLAIM**

The ornamental design for a front bumper for vehicle as shown and described.

DESCRIPTION

The patent or application file contains at least one drawing executed in color. Copies of this patent or patent application publication with color drawing(s) will be provided by the Office upon request and payment of the necessary fee.

1. Front bumper for vehicle

1.1 : Front

1.2 : Back

1.3 : Left

1.4 : Right

1.5 : Top

1.6 : Bottom

1.7 : Perspective

FIG. 1.1 to FIG. 1.7 are drawings showing an embodiment of a front bumper for vehicle. The broken lines and the perspective area with dark blue in the drawings show portions of the front bumper for vehicle which form no part of the claimed design.

1 Claim, 7 Drawing Sheets
(7 of 7 Drawing Sheet(s) Filed in Color)
